UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

PUSH-BUTTON CIRCUIT-CONTROLLER.

1,206,454.

Specification of Letters Patent. Patented Nov. 28, 1916.

Application filed August 18, 1914. Serial No. 857,294.

To all whom it may concern:

Be it known that I, RAY H. MANSON, a citizen of the United States, and a resident of Elyria, in the county of Lorain and State of Ohio, have invented certain new and useful Improvements in Push-Button Circuit-Controllers; and I do hereby declare the following to be a full, clear, and exact description of the invention, such as will enable others skilled in the art to which it appertains to make and use the same.

My invention relates to push button circuit controllers, and has for its object the provision of a device of this character which presents a large unprotected operating area, and which will be operated no matter what part of the operating area is touched, my object being to provide a circuit controller which can be operated without detracting the attention of the driver from the operation of the vehicle.

Another object of my invention is the provision of a button which can be used either where the conductors approach from the side or from the bottom of the vehicle.

Other objects of my invention and the invention itself will probably be better understood from a description of an embodiment of my invention.

Figure 1 is a side elevation of an embodiment of my invention showing one corner in section and the conductors approaching from the side. Fig. 2 is a cross-section through the embodiment of the invention illustrated, showing the button in switch operating position when tilted. Fig. 3 is a section showing the button in switch operating position when depressed. Fig. 4 is a side elevation of the embodiment illustrated in Fig. 1, showing the button used as a conductor concealing button. Fig. 5 is a front elevation of the casing member. Fig. 6 is a back elevation of the casing member. Fig. 7 is a bottom plan view of the button.

Referring now to the embodiment of my invention illustrated in the drawing, at 8 is shown the casing member which is preferably made cylindrical up to a point 9, where it is pressed inward to form a shoulder 10 for a purpose to be described. The casing is then extended upwardly, as shown at 11 in a substantially cylindrical shape of less diameter than the lower portion, but concen-

tric therewith. The top of the casing is turned over to form a flange 12 for a purpose to be described. Means are provided for fastening the casing to a portion of the vehicle or other object, here shown as a pair of ears 13, which are formed upon the bottom of the casing, extending parallel therewith, and which may be integral with the casing. These ears are perforated, as shown at 14 through which screws may be inserted to attach the button to some object.

The casing is provided with an opening 15 upon one side, which is here shown as arc-shaped, and as cut through to the bottom of the wall of the casing. This opening is provided for the introduction of the conductors into the casing when it is desired to mount the button on a flat surface and run the conductors in from the side, as illustrated in Fig. 1. Here conductors 20 and 21 are shown as coming in from the side. The conductors 20 and 21 are associated with the source of current 22 and an electro-responsive device 23, here illustrated as an automobile horn. The push button is shown at 25. It is of large area, and preferably of flat dome shape, as illustrated, and projects 80 high above the edge of the casing 11, so that it may be caught and depressed without danger of engaging the casing. The button may be made of an integral piece of suitable material, such as hard rubber or gutta percha. 85 A catch member 30 is formed upon said button preferably around the edge, which will engage with the flange 12, when the button is in normal position, as will be apparent from Figs. 2 and 3. A projection 31 is 90 formed in the center of the button. This projection may be integral with the button, as illustrated in the drawing. The space between the members 30 and 31 is hollowed out, as shown at 32, to insure that there will 95 be no interference between this button and the terminal screws when the button is depressed. The terminal screws are shown at 40 and 41. They are threaded in bed plates 42 and 43, which are in turn embedded in a base 44 mounted in the bottom portion of the casing 8. This base may be of insulating material, and its top edge engages the shoulder 9, securely holding the base in position in the casing. Contact springs 50 and 51 are 100 connected respectively to the contact screws

40 and 41. These springs are normally in disengaged position, leaving the circuit open, and the spring 50 serves to elevate the button 31 to normal or switch unactuated position.

10 The contact 51 is provided with a relatively long limb extending along the top of the base and with a relatively short limb extending upward substantially perpendicular thereto, to contact with the free end of the contact 50. The spring contact 50 is connected at one end by 40 to the base and doubled back to extend under the member 31, as shown in Figs. 2 and 3.

15 When it is desired to operate the horn, the driver reaches in the direction of the button without taking his attention from the driving of the vehicle, and strikes the same. Owing to the large area of the button and 20 the fact that it projects high above the casing, there is no danger of his missing the button or striking the casing instead of the button. Should he strike the button upon the edge and press it until operated, as 25 shown in Fig. 2, the button will pivot upon the point of engagement between the portion 30 of the button and the flange 12 opposite the point to which the pressure is applied and rotate about such point, the projection 30 31 depressing the spring 50 until it engages the spring 51, and closing the circuit. Should the driver press down the central portion of the button 25, said button will descend straight down and close the contacts 35 in the manner shown in Fig. 3.

The base member is provided with a channel 60, shown in Fig. 1, through which the conductors are led to the contact screws. This channel is provided with a port 61 in 40 the bottom of the base member and a port 62 in the side of the base member, the port 62 registering with the opening 15 in the casing when the parts are in the position shown in Fig. 1. These ports may inter- 45 communicate, as shown at 90; then the conductors can be transferred from one to the other without disconnecting them. However, when it is desired to conceal the conductors and introduce them from the bot- 50 tom of the button, the casing is turned to the position shown in Fig. 4, where the port 62 is closed by the solid wall of the casing, and the conductors enter the channel 60 through the port 61.

55 It will be readily understood that numerous and extensive departures may be made from the form and details illustrated in the embodiment shown in the drawing. This form and these details have been illus- 60 trated for the purpose of describing the invention, and not that the invention is to be limited to such form and details.

I claim:

1. In a push button circuit controller, the 65 combination of a base of insulating material,

a pair of contacts mounted thereon, one of said contacts consisting of an angular piece having a long arm extending along the top of said base and a short arm turned up substantially at right angles thereto, means to connect the long arm of the angular piece to the base, the other of said contacts being a spring contact doubled back in form and connected at one end to the top of said base, the free end of the spring contact being normally above the short arm of the angular piece and adapted to engage the same when depressed, a casing about said base projecting above the same, an annular inwardly turned flange upon the top of said casing 70 integral therewith substantially at right angles to the walls of the casing, a dome-shaped push button of substantially the same area as the base mounted with its bottom portion inclosed in said casing, an annular 75 catch upon the bottom edge of said button loosely engaging with its top side the underside of said casing normally and adapted to be slid or tilted in said casing, a downwardly projecting member on said button 80 normally engaging the doubled back spring, said spring normally holding said button with its flange engaging the flange on the casing, said button when either depressed or tilted causing through said projection the 85 depression of the free end of the doubled, back contact spring and causing it to engage the short arm of the angular piece to close an electric circuit.

2. In a push button circuit controller, the 100 combination of a base of insulating material, a pair of contacts mounted thereon, one of said contacts consisting of an L-shaped piece with its long arm extending along the top of the base and connected thereto and 105 its short arm projecting upwardly from the top of the base, a second contact consisting of a doubled back piece of metal, one arm of which is connected to the top of the base and the other arm of which is bent upwardly and 110 positioned over the short arm of the L-shaped member, the short arm of the L-shaped member being in the path of movement of the free arm of the doubled back member, a casing about said base projecting 115 above the same having a catch on the top of the casing extending inwardly, a push button of substantially the same area as the base provided with a catch adapted to coöperate with the catch on the casing to maintain the 120 button in position on the casing, the free arm of the doubled back contact engaging a portion of the button and maintaining it in normal position, said button being both de- 125 pressible and tiltable in the casing and when either depressed or tilted causing the free end of the doubled back contact to engage the short arm of the L-shaped contact clos- 130 ing an electric circuit.

3. In a push button circuit controller, the 135

combination of a cylindrical base of insulating material, a pair of contacts mounted thereon, one of which is doubled back, means to connect one of the legs of the doubled back contact to the top of the base, the other leg of the doubled back contact being free and bent upward from the upper surface of the base, said doubled back member being made of spring material; the second of said contacts being mounted upon the base with a portion in the path of movement of the free arm of the doubled back contact, a cylindrical casing mounted about the base member and extending above the same, a push button of substantially the same area as the base mounted in the casing above the base, said push button extending above the casing, means including a catch on the casing and on the button for limiting the upward movement of the button in the casing, the free arm of the doubled back contact engaging a portion of the button and normally pressing it upward in the casing and causing the catch members on the casing and the button to engage, said button being both tiltable and depressible in the casing and when depressed or tilted causing the free end of the doubled back contact to engage a portion of the other contact and close an electric circuit.

4. In a push button circuit controller, the combination of a base member having a channel cut therein, a port to said channel in the bottom of the base member and a port to said channel in the side of the base member, a casing about said base member and rotatable with respect thereto, and an opening in said casing adapted to register with the port in the side of the base member.

5. In a push button circuit controller, the combination of a base member, a channel in said member, a port to said channel in the side of said base member, a casing rotatably mounted on said base and provided with an opening for registering with the side port in the base member and with a solid wall for covering the port in the base member.

6. In a push button circuit controller, the combination of a side wall having a port therein, a bottom wall having a port therein, said ports being intercommunicating, electrical terminals within said walls, said ports adapted to admit conductors to said circuit controller and means to connect said terminals together.

7. In a push button circuit controller, the combination of a cylindrical casing, the upper portion of the casing being of less diameter but concentric with the lower portion of the casing, a shoulder formed on the casing at the top of the portion of larger diameter, a base member forming a bottom wall for the casing within said casing and having its upper corner in engagement with

said shoulder and its bottom being flush with the bottom of the casing, a pair of electrical terminals on said base member, a port in the side of said casing through which conductors may be led to the terminals, a corresponding port in said base member, said casing being rotatable to close said port in said base member, a pair of electrical contacts connected to said terminals one of which is a spring contact normally stressed 75 away from the other contact and from the bottom of the casing, an annular flange formed upon the upper end of the casing by turning it inward, a flat dome shaped push button of relatively large area extending 80 high above the casing mounted with its lower portion in the casing, an annular catch formed upon the lower outside edge of the button and integral therewith, loosely 85 engaging the flange on the top of the casing normally and permitting sliding and tilting movement thereon, the bottom of the button being hollowed out to avoid the terminals, and a projection on the bottom of the button in the central part thereof integral with the button normally engaging the spring contact, said button when depressed bodily sliding within the upper portion of the casing and causing the depression of the spring contact to engage the 90 other contact, said button when depressed at a point adjacent its side rocking about a point of engagement between the annular catch on the channel and the flange on the top of the casing to cause the depression of 95 the spring contact and its engagement with the other contact, substantially as described.

8. In a push button circuit controller, the combination of a cylindrical base of insulating material, a pair of contacts mounted thereon, one of said contacts consisting of an angular piece having its long arm extending along the top of said base and its short arm turned up at substantially right angles thereto, the long arm of said angular piece being perforated and a screw in said perforation for connecting the angular piece to the base, the other of said contacts being a spring contact connected at one end to the top of said base, the free end of the spring contact being normally above the short arm of the angular piece and adapted to engage the same when it is depressed, a cylindrical casing about said base projecting above the same, an annular inwardly turned flange upon the top of said casing integral therewith and substantially at right angles to the walls thereof, a flat, dome-shaped push button of large area, with its bottom portion inclosed in said casing, an annular catch upon the bottom edge of said button loosely engaging with its top side the under side of the flange upon the casing normally and permitting sliding and tilting movement thereon, said button being slid-

110
115
120
125
130

able in said casing and normally held by the spring contact with the catch against the flange on said casing, and a projection upon the bottom of the button normally engaging with its lower end the free end of said contact spring, said button being tilt-
able in said casing and when depressed or tilted, causing through said projection the depression of the free end of the contact.

spring to engage the short arm of the angular piece to close an electric circuit. 10

In witness whereof I have signed my name in the presence of two witnesses this 12th day of August, 1914.

RAY H. MANSON.
